UNITED STATES PATENT OFFICE.

ALTON GILLON RAY, OF PITTSBURGH, PENNSYLVANIA.

DESIGN FOR A PASSENGER-LOADING PLATFORM FOR STREET RAILWAYS.

60,572.

Specification for Design.

Patented Mar. 7, 1922.

Application filed August 5, 1920. Serial No. 401,525. Term of patent 3½ years.

To all whom it may concern:

Be it known that I, ALTON G. RAY, a citizen of the United States, residing at Pittsburgh, in the county of Allegheny and State of Pennsylvania, have invented a new, original, and ornamental Design for a Passenger-Loading Platform for Street Railways, of which the following is a specification.

Referring to the drawing—

Figure 1 is a perspective view of a passenger loading platform for street railways showing my new design.

Figure 2 is a top plan view of the same; and

Figure 3 is an end elevation.

I claim:—

The new, original and ornamental design for a passenger loading platform for street railways, substantially as shown.

In testimony that I claim the foregoing as my own I have hereto affixed my signature.

ALTON GILLON RAY.
